US00D775250S

(12) **United States Design Patent** (10) **Patent No.:** **US D775,250 S**
Snead et al. (45) **Date of Patent:** **** Dec. 27, 2016**

(54) **PORTABLE WELD CONTROLLER**

(71) Applicant: **Lincoln Global, Inc.**, City of Industry, CA (US)

(72) Inventors: **Jamil Snead**, San Diego, CA (US); **Stephen Cole**, Bonita, CA (US)

(73) Assignee: **LINCOLN GLOBAL, INC.**, City of Industry, CA (US)

(**) Term: **15 Years**

(21) Appl. No.: **29/544,499**

(22) Filed: **Nov. 4, 2015**

(51) LOC (10) Cl. **15-09**

(52) U.S. Cl. **USPC .....** **D15/144**

(58) **Field of Classification Search**

USPC D15/122, 144, 144.1, 144.2
See application file for complete search history.

(57) **CLAIM**

The ornamental design for a portable weld controller, as shown and described.

DESCRIPTION

FIG. 1 is a front perspective view of a portable weld controller showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings depict unclaimed environmental subject matter.
